[57] CLAIM

The ornamental design for a toothbrush handle, as shown and described.

DESCRIPTION

FIG. 1 is a top plan view of the toothbrush handle showing our design;

FIG. 2 is a left side elevational view thereof;

FIG. 3 is a bottom plan view thereof;

FIG. 4 is a right side elevational view thereof;

FIG. 5 is an elevational view as seen from the head end thereof;

FIG. 6 is an elevational view as seen from the handle end thereof;

FIG. 7 is a perspective view thereof from the top of the brush handle; and,

FIG. 8 is a perspective view thereof from the bottom of the brush handle.

The broken line showing of bristles is for illustrative purposes only and forms no part of the claimed invention.
